UNITED STATES PATENT OFFICE.

RAYMOND A. HEISING, OF EAST ORANGE, NEW JERSEY, ASSIGNEE TO WESTERN ELECTRIC COMPANY, INCORPORATED, OF NEW YORK, N. Y., A CORPORATION OF NEW YORK.

CIRCUIT CONNECTION OF ELECTRON DISCHARGE APPARATUS.

Application filed October 11, 1916. Serial No. 124,953.

To all whom it may concern:

Be it known that I, RAYMOND A. HEISING, a citizen of the United States, residing at East Orange, in the county of Essex and 5 State of New Jersey, have invented certain new and useful Improvements in Circuit Connections of Electron Discharge Apparatus, of which the following is a full, clear, concise, and exact description.

10 This invention relates to circuit connections for electron discharge apparatus and more especially to electron discharge apparatus of the type in which a filamentary cathode enclosed in an evacuated vessel is 15 provided with means for heating the filament to incandescence to cause it to emit electrons, which may serve to convey a space current to a cooperating anode enclosed in the same envelope. Such devices may be 20 used for producing X-ray or rectifying alternating currents, or when provided with a controlling grid, as in vacuum tubes of the audion type, for amplifying variable currents, detecting wireless signals, and for 25 various other purposes.

It has been customary prior to my invention to provide, for heating the cathode, a direct current source, such as a battery or direct current generator. The external circuit 30 connections to the cathode have been generally made to one side of the filament, and as a result all parts of the filament have not been of the same potential with respect to the anode or the grid, the difference between 35 extreme ends being equal to the voltage impressed upon the filament. Where a source of direct current is employed, this voltage or difference of potential is constant, and therefore will not produce variations in the 40 operation of the device. It is, however, more convenient in some cases to employ an alternating current for heating the filament, this being particularly true when a large number of such tubes are operated simultaneously, requiring a considerable amount 45 of power for the heating of the filament. Upon the substitution of such an alternating current heating source for the filament, the variations of potential difference between 50 the grid and filament or the plate and filament which are thereby introduced,

may seriously affect the efficient operation of the device.

The object of this invention is to provide an improved circuit connection for electron 55 discharge devices, whereby alternating current may be employed for heating the filament, and the disadvantage above mentioned, as well as others which will hereafter appear, may be overcome.

60 In the practical application of my invention, current for heating the filament is obtained directly from an alternating current generator or from the secondary of a transformer, and the connections from anode and grid to the cathode are made to some point 65 in the filament circuit which has a potential equal to the average potential of the filament which in general is that of the middle point of the filament. When the connections are made in this way, the average 70 voltage or difference of potential at any instant between different portions of the cathode and the grid, and the anode, due to the heating current, will be zero.

75 The invention will be better understood by reference to the accompanying drawing and following specification, in which Fig. 1 represents an embodiment of this invention shown in connection with an electron discharge device; Fig. 2 is a modification of 80 Fig. 1; Fig. 3 shows how this invention may be applied simultaneously to a plurality of electron discharge devices; and Fig. 4 illustrates how a non-inductive resistance may 85 be employed to obtain the desired average potential of the filament with respect to the grid and cathode.

90 Referring to Fig. 1, there is shown a vacuum tube 10 of the audion type containing the usual heated filament 12, grid 13 and plate 14. Connected to the input terminals 12 and 13, is some source of variable currents to be amplified or rectified or otherwise operated upon. In this case there is shown 95 a microphone transmitter 16 in circuit with a battery 17 and the primary 18 of the transformer 19. The secondary 20 of said transformer has one terminal connected to the grid 13, and the other terminal connected to 100 the filament 12 in a manner hereafter described. Across the terminals of the second-

ary winding 20 is connected a resistance 21 for the purpose of making the impedance of the input circuit, as viewed from the primary coil 18, the same for all impressed frequencies. The output circuit is of any well-known form, such as that shown, and comprises a source of direct current 24 and the primary 25 of a transformer 26. This output circuit is connected to the plate 14 in the usual manner, and to the filament in a manner to be described. The secondary 27 of the transformer 26 may be connected to any suitable apparatus adapted to utilize the output energy. The filament 12 is shown as supplied with alternating current from the generator 29, the said generator being coupled in any suitable manner to the filament, as by a transformer 30. The usual connection of the filament to the external circuits, in view of the prior art, would be to connect one terminal of the coil 20 and the negative pole of the battery 24 to one terminal of the filament. This, however, leads to the disadvantages mentioned above, that there will be continual variations in the potential between the filament and grid, and between the filament and plate. To overcome this disadvantage, a connection is made from the middle point of the filament 12, as shown at 31, to a point 32 common to both the input and output circuits. As a result, the average voltage or difference of potential between different portions of the cathode and grid and anode, due to the heating current, will be zero.

One inconvenience of the arrangement as shown in Fig. 1 is the necessity of having an additional terminal coming through the wall of the vacuum tube 10. This inconvenience may be overcome by arranging the circuit as shown in Fig. 2. In this circuit there is shown a similar source of alternating currents adapted to be used as the input of a tube 35, the said tube being similar in every respect to that shown in Fig. 1. The external circuit, comprising the input and the output circuits, is also similar in every respect. In this Fig. 2, however, the point 32 of the circuit, which is common to both the input and the output circuits, is connected to the middle point of the secondary 36 of the transformer 37. The primary 38 of this transformer is supplied from the alternating current generator 29, and in general it will be desirable to have some regulating device, such as 39, to control the current delivered by the generator. In this case again the same purpose is accomplished as in Fig. 1, namely, that the external circuits are connected to such a point in the filament circuit that the average difference of potential at any instant between different portions of the cathode and grid and anode, due to the heating current, will be zero.

65 In this Fig. 2 there are shown two con-

densers 41 and 42, each connected across one-half of the transformer secondary 36. These condensers are used for the purpose of affording a low impedance path for the alternating currents in the input and output 70 circuits, but they should be of such dimensions as to offer a reasonably high impedance to the alternating current from the generator 29.

Referring to Fig. 3, the invention is 75 shown adapted to a wireless system such as is described in the U. S. Patent No. 1,388,450 to Colpitts and Arnold, issued August 23, 1921. In this figure there is shown an incoming circuit 45, which, by means of the 80 transformer 46, may impress suitable signals upon the input circuit of a bank of audion amplifiers 48. In general, for such a system as shown here, the incoming signals will consist of high frequency oscillations modulated in accordance with low frequency signals. Each of the amplifiers 48 comprises the usual filaments, plates and grids. In this figure the filaments are shown as connected in parallel, and the 85 plates are similarly shown as connected in parallel, and the grids are also shown as connected in parallel. The usual direct current source 50 is supplied for the output circuit, this source consisting of storage 90 batteries or a direct current generator. The output circuit is finally connected in a suitable manner to an antenna system 51, all in a manner fully described in the above mentioned application of Colpitts and Arnold. 100

The filaments are shown in this figure as being adapted to be heated by an alternating current in accordance with this invention, the generator 29 and transformer 37 being of the same form as shown in Fig. 2. In 105 some cases, however, it may be inconvenient or impossible to make a connection to the middle point of the transformer secondary 36. Accordingly, there is placed across the terminals of said secondary an impedance 110 or choke coil 52, and from the middle point of this impedance 52 a connection is made to the point 32 common to the input and output circuits of the amplifier system. The impedance of this coil is preferably sufficiently high to prevent the passage of much current from the generator 29, but should have a reasonably small direct current impedance for the current from the battery 50. As shown in the drawing, both halves of retard coil 52 are wound in the same direction 115 so that the retard coil acts non-inductively to signaling currents received from line 45. As described in connection with Fig. 2, there are shown two condensers 53 and 54, each 120 connected across one-half of the impedance 52, these condensers being supplied to offer a low impedance path for the high frequency current to be amplified and transmitted from the antenna 51. As in Fig. 2, 130

however, these condensers should be of sufficiently small dimensions to offer a high impedance to the alternating current from the generator 29.

5 This impedance may, of course, be looked upon as an auto-transformer with the connection from the point 32 to the middle of of said auto-transformer. It is apparent that the transformer 37 of this Fig. 3 may 10 therefore be dispensed with if the generator 29 is of a suitable voltage. Also this impedance 52 may, obviously, be used in connection with the circuits of Fig. 1 or Fig. 2 either with or without the transformers 15 shown in said circuits.

The impedance 52 may, furthermore, be replaced by a non-inductive resistance such as shown in Fig. 4. In such a case the circuit connections will be similar in every 20 respect, with the exception that the negative pole of the battery should be connected to one end 56 of the resistance 54. This is preferable to having the connection made to the middle of the resistance 54, in order that 25 the space current from the filament may pass directly to the battery 55 without having to pass through the high resistance 54. In view of the fact that the current in the input circuit is exceedingly small, it will be 30 permissible to make the contact from the input circuit directly with the middle point 57 of the resistance 54.

This arrangement has the disadvantage 35 that the voltage between the filament and the anode will fluctuate slightly in view of the variable fall of potential along the half of the resistance from 56 to 57. Such disadvantage may be overcome or neutralized, however, by sliding the point of contact of 40 the input circuit from the point 57 to the point 58 slightly to one side, and by such an amount that the fall of potential between 57 and 58 multiplied by the amplifying coefficient of the amplifier shall be equal and opposite to the fall of potential between the 45 points 56 and 57.

A number of circuits have now been described, in each of which an alternating current is used for heating the filament or filaments of a vacuum tube system, and in 50 which the deleterious effects arising from potential variations are overcome. It is to be understood, however, that the invention is not limited to the circuits shown, and 55 that numerous changes may be made in the circuits without departing from the spirit of this invention.

What is claimed is:

1. The combination with an electron discharge device comprising an evacuated envelope having therein a filamentary cathode and a cooperating anode, of a transformer connected to a source of alternating current and having its secondary connected to said 60 cathode for heating it to incandescence, an

external circuit connection between said anode and the central point in the secondary winding of said transformer, and a condenser connected across each half of said secondary adapted to offer a low impedance path to 70 input frequencies and a high impedance path to the heating generator frequency.

2. The combination with a plurality of electron discharge devices of the audion type 75 each comprising an evacuated envelope having a filamentary cathode and a discharge controlling grid, the grids being connected in parallel and the filaments being connected in parallel, of a transformer connected to a source of alternating current and having its 80 secondary connected to said cathodes for heating them to incandescence, and an external connection from said grids to the central point in the secondary winding of said transformer.

3. In combination a vacuum tube having 85 an anode, a cathode and a control electrode, a source of alternating current for heating said cathode, an impedance between said source and said cathode, a connection between said control electrode and the midpoint of said impedance, and a condenser across said impedance.

4. In combination a vacuum tube having 90 an anode, a cathode and a control electrode, a source of alternating current for heating said cathode, an impedance between said source and said cathode, a connection from the midpoint of said impedance to said control electrode, and a condenser across each 100 half of said impedance.

5. An electron discharge device having a 105 thermionic cathode and an input circuit, a transformer connected to said cathode for supplying heating current thereto, a path in shunt to the secondary of said transformer, and a connection from said input circuit to a point on said path having a potential substantially equal to the average cathode potential.

6. An electron discharge device having a 110 thermionic cathode and an output circuit, a transformer connected to said cathode for supplying heating current thereto, a path in shunt to the secondary of said transformer, and a connection from said output circuit to a point on said path having a potential substantially equal to the average cathode potential.

7. An electron discharge device having a 120 thermionic cathode and an input and an output circuit, a transformer connected to said cathode for supplying heating current thereto, a path in shunt to the secondary of said transformer, and a connection from said circuits to a point on said path having a potential substantially equal to the average cathode potential.

8. A signaling system comprising an electron discharge device having a thermionic 130

cathode, an input circuit and an output circuit, a transformer connected to said cathode for supplying heating current thereto, a path in shunt to the secondary of said transformer, said path being of high impedance to heating current and low impedance to signaling currents, and a connection from said

circuits to a point on said path having a potential substantially equal to the average cathode potential.

10

In witness whereof, I hereunto subscribe my name this 9th day of October, A. D. 1916.

RAYMOND A. HEISING.
